(57) **CLAIM**

The ornamental design for a reticle for telescopic gunsight, as shown and described.

DESCRIPTION

FIG. 1 is a perspective view of a reticle for telescopic gunsight showing our new design;

FIG. 2 is a front elevation view thereof;

FIG. 3 is a bottom plan view thereof; the top plan view being identical,

FIG. 4 is a rear elevation view thereof; and,

FIG. 5 is a right side elevation view thereof; the left side elevation view being identical.
